(57) **CLAIM**

The ornamental design for a tricycle with removable push bar, as shown and described.

DESCRIPTION

FIG. 1 is a perspective view of the tricycle with removable push bar showing my new design;

FIG. 2 is a front view thereof;

FIG. 3 is a right side view thereof, the left side being a mirror image;

FIG. 4 is a top view thereof;

FIG. 5 is a bottom view thereof;

FIG. 6 is a back view thereof;

FIG. 7 is a perspective view of the tricycle of FIG. 1, shown without the removable push bar;

FIG. 8 is a front view of the tricycle shown in FIG. 7;

FIG. 9 is a right side view of the tricycle shown in FIG. 7, the left side view being a mirror image;

FIG. 10 is a top view of the tricycle shown in FIG. 7;

FIG. 11 is a bottom view of the tricycle shown in FIG. 7; and, FIG. 12 is a back view of the tricycle shown in FIG. 7.
